C. F. JENKINS

ROTARY RELAY

Filed July 21, 1924

C. Francis Jenkins Inventor

UNITED STATES PATENT OFFICE.

CHARLES FRANCIS JENKINS, OF WASHINGTON, DISTRICT OF COLUMBIA.

ROTARY RELAY.

Application filed July 21, 1924. Serial No. 727,271.

This invention relates to devices for controlling the speed of distant motors, and has for its particular object means for controlling motor speeds by radio.

- 5 With this and other objects in view the invention consists in the novel details of construction and combinations of parts more fully hereinafter disclosed and particularly pointed out in the claims.
- 10 Referring to the accompanying drawing, which is a schematic drawing of the device, A is a radio antenna; B a ground; and C a receiving set; and C¹ an amplifier. D is a miniature, synchronous motor taking current from the amplifier set; D² a pinion on the motor shaft, engaging with a larger gear D³. E is the power motor it is desired to control; F the current supply therefor; G an adjustable resistance in circuit with the 20 motor and power supply. On the shaft of the large motor and the jack shaft of the small motor are contacting dogs H and I insulated from their respective shafts, and having brushes K and M in contact with the 25 hubs of each. These brushes are in a circuit which cuts out all or part of the resistance G. N is a shortcircuiting push button. R is a radio photo camera which has co-acting therewith the lamp S, electrically in circuit with the amplifier C¹.

The operation of the device is as follows—

Let it be assumed that the radio set is receiving signals with a given frequency, for example, 540 cycles, the frequency often employed in radio photography by applicant.

If then the circuit is closed through the motor E, the resistance G and the current supply F, the motor E will rotate, and because the dog I pushes the dog H around, the rotor of motor D will be dragged around, but at a speed below the speed necessary to get it into step with the incoming radio signals.

When, however, the shortcircuiting push-button switch N is closed the motor E speeds up until the small motor D is running faster than normal. If now the button N be released the motor E will slow down because of the resistance now in the circuit. As a

result the motor D will presently fall into 50 step with the incoming radio current frequency and continue to run at that speed.

But the motor E continues to lag until contact piece I catches up with contact piece H, and the resistance G is momentarily cut 55 out, whereupon, the motor speed increasing, the contact is broken and the motor slows down again.

This cycle is repeated indefinitely, but as the lagging to close the shortcircuit through 60 M I H K and the acceleration to open it is such a small decrement and increment respectively, the lack of steadiness in the rotation of the motor E can not be detected.

From the amplifier current is put through 65 the lamp S, and, as the current is a modulated current, the intensity of the light varies with the variation in the strength of the current. The radio-carried current has a constant frequency (540 perhaps) but having a modulated character, this latter characteristic can be usefully employed to fluctuate the intensity of the light S, the one electric current serving the two purposes.

What I claim, is—

1. In combination, a power motor, a control motor, a rotatable contact member driven by said control motor at a definite speed, a second rotatable contact member driven by the power motor in the path of 80 the first contact member and at a lower speed than the first, said contact members co-acting when engaged to close a circuit to cause said power motor to increase its speed, and means independent of said contact members for closing said circuit.

2. In a device of the character described, the combination of a synchronous motor, a contact member rotated by said motor, a second motor, a contact member on said second 90 motor located to interfere with the free rotation of said first-mentioned contact member, and a current supply controlled by said contact members.

3. In combination, a power motor, a control motor, a rotatable contact member driven by each motor, said contact members co-acting to close a circuit to control the

speed of the power motor, and means independent of said contact members for closing said circuit.

4. In combination, a power motor, a control motor, mechanical means connecting said motors comprising two co-acting elements having limited differential movement for initiating the operation of the control

motor by the power motor, and means responsive to differential movement between 10 said elements for controlling the speed of the power motor.

In testimony whereof I have affixed my signature.

CHARLES FRANCIS JENKINS.
